UNITED STATES PATENT OFFICE.

WILLIE CLYDE EATON, OF LEAD HILL, ARKANSAS.

TRACK-LINER.

1,234,738.

Specification of Letters Patent. Patented July 31, 1917.

Application filed September 23, 1916. Serial No. 121,858.

To all whom it may concern:

Be it known that I, WILLIE CLYDE EATON, a citizen of the United States, residing at Lead Hill, in the county of Boone and 5 State of Arkansas, have invented certain useful Improvements in Track-Liners, of which the following is a specification, reference being had therein to the accompanying drawing.

10 This invention relates to improvements in track liners, one object of the invention being a portable machine which may be moved from place to place and which is provided with means for engaging a track rail to line 15 the same in the usual manner.

A further object of this invention is the provision of a machine of this type which is provided with a main frame carrying a lining rack bar and a ratchet actuated gear 20 wheel so that such rack bar may be reciprocated in combination with means for elevating one end of the machine so that the proper pull may be exerted upon the rack bar, there further being provided means for 25 driving in the ground when necessary to hold the machine stationary.

A further object of the invention is the provision of a machine of this type which is simple, durable and inexpensive in 30 construction and thoroughly efficient and practical in use.

In the accompanying drawings:

Figure 1 is a side elevation of the complete machine in use.

35 Fig. 2 is a top plan view thereof.

Fig. 3 is a bottom plan view thereof.

Fig. 4 is a longitudinal sectional view through the complete machine.

40 Figs. 5 and 6 are detail views of various parts.

Referring to the drawings, the numeral 10 designates the two end cross bars which are slit as at 11 for the slidable reception of the liner bar 12 which is provided upon its 45 upper surface with the rack bar 13. One end of this bar is bifurcated as at 14 for the reception of the reduced end 15 of the swinging section 16 thereof, a hook like latch or locking member 17 being provided to hold 50 this member rigid with the liner bar as the pin 18 constitutes a hinge for said swinging member.

The terminals of the bars 10 are each provided with a rectangular opening 19 for the 55 reception of the square shanks 20 of the ground engaging members or blades 21, such

square shanks being provided with slidable limiting members 22 and the keys 23. These ground engaging members serve to anchor the device in the track bed between the rails. 60

Attached to the under side of the bars 10 extending longitudinally and directly below the liner bar is the ground engaging plate 24 being supported in this position preferably through the instrumentality of the spacing 65 bars 25 and 26. This plate 24 serves to brace the anchorage of the cross bars during the actuation of the device as will become apparent.

Attached to the upper side of the two 70 cross bars 10 and in spaced relation with each other, are the two triangular side plates 27 which together with the cross bars 10 form the supporting frame in which side plates is journaled a shaft 28 which carries 75 the large gear or ratchet wheel 29, the teeth of this wheel being in engagement with the teeth of the liner bar at all times. Mounted for oscillation upon the shaft are the two terminals 30 of the operating handle 31, 80 said terminals being adapted to fit astride of the ratchet wheel so that the two oppositely disposed ratchets 32 and 33 carried thereby will engage the ratchet wheel and cause rotation thereof in the desired direction as the handle or lever is oscillated. A selective latch or lock 34 for holding either 85 one of the pawls is provided so that the liner bar may be reciprocated in either direction. 90

Attached to each one of the triangular members of the frame is a handle 35 by means of which the present invention may be carried from place to place.

To prevent the locking member or latch 95 17 from working out of the hole in the swinging terminal 16 for said latch or member, the latter has threaded thereon a nut 16' although this latch or member 17 may be fastened in any other way. 100

The operation of the invention may be reviewed as follows:

Assuming that the device has been assembled in the manner described and that the ground engaging members 21 are anchored 105 in the track bed between the rails and that one end of the liner bar is engaged adjacent one rail and the pivoted section thereof is engaged adjacent the inner surface of the other rail, by swinging the lever 31 one of 110 the pawls 33 being engaged in the gear causes a longitudinal movement of the bar in

one direction so as to shift the rails and cross ties forming the track bed in the corresponding direction. During this actuation the ground engaging plate 24 having 5 one end engaged in the ground and arranged at an inclination to the frame, serves as a means for bracing the anchorage of the ground engaging members 21 and increases the rigidity of the device to insure an effective operation. Of course by adjusting 10 the selective latch 34 the other ratchet 32 may be arranged to engage the gear during the actuation of the lever when it is desired to shift the liner bar in an opposite 15 direction. Obviously, the nut 16' co-operates with the hook-like latch in maintaining the pivoted section 16 substantially rigid and in alignment with the bar 12, this section being used to facilitate the application 20 of the liner bar between the rails.

It will be understood that the above description and accompanying drawings comprehend only the general and preferred embodiment of my invention and that various 25 minor changes in detail of construction, proportion, and arrangement of the parts may be made within the scope of the appended claims and without sacrificing any of the advantages of my invention.

30 What I claim, as new, is:

1. A track liner including a supporting frame embodying spaced cross bars and vertically arranged side plates carried thereby, means for anchoring the frame between the 35 rails of a track bed, a liner bar slidably mounted in and movable transversely of the cross bar and having the upper surface

provided with rack teeth, one end of the liner bar being adapted to engage the inner faces of one rail, a pivoted section on the other end of the liner bar adapted for engagement with the inner faces of the other rail, means for removably locking the section in a substantially rigid position and in alignment with the liner bar, a gear rotatably mounted between the side plates and engageable with the teeth of the bar, an oscillatory lever, and selectively operated pawls pivoted to the lever and engageable with the gear whereby when the lever is actuated the liner bar will be moved in either direction.

2. A track liner including a supporting frame embodying spaced cross bars and vertically arranged side plates carried adjacent 55 the respective ends thereof, blade like ground engaging members mounted in the respective ends of the cross bars for anchoring the frame between the rails of a track bed, an inclined ground engaging plate carried 60 beneath the frame for bracing the anchorage of the frame, a liner bar slidably mounted in the cross bars and adapted for engagement with the inner faces of the rails of the track bed and having the upper surface 65 provided with rack teeth, a gear rotatably mounted between the side plates and engageable with the teeth of the bar, an oscillatory hand lever, and selectively operated pawls 70 pivoted to the lever and engageable with the gears whereby when the lever is oscillated the liner bar is moved in either direction.

In testimony whereof I affix my signature.

WILLIE CLYDE EATON.
